(57) **CLAIM**

The ornamental design for a sump pump holding device as shown and described.

DESCRIPTION

FIG. 1 is an isometric view of a sump pump holding device showing my new design;

FIG. 2 is a front view of the sump pump holding device of FIG. 1;

FIG. 3 is a rear view of the sump pump holding device of FIG. 1;

FIG. 4 is a first side view of the sump pump holding device of FIG. 1;

FIG. 5 is a second side view of the sump pump holding device of FIG. 1;

FIG. 6 is a top view of the sump pump holding device of FIG. 1; and,

FIG. 7 is a bottom view of the sump pump holding device of FIG. 1.

In the drawings, the portions of the sump pump holding device shown in broken lines depict unclaimed portions of the article and form no part of the claimed design.
